METHOD AND DEVICE FOR SEPARATING
COHERENT TOBACCO LEAVES

Valentin Lorentz, Dresden-Hohendolzschen, Germany, assignor to Carl Bergmann, Dresden-A., Germany

Application May 29, 1931, Serial No. 541,077
In Germany July 28, 1930

8 Claims. (Cl. 131—60)

The present invention relates to a method and device for separating coherent tobacco leaves.

A known method of separating tobacco leaves that stick together on being removed from bales 5 consists in exposing the bunches to the action of an air current which counteracts the inertia of the bunches or bundles and divides them into individual leaves.

The present invention employs other means 10 by providing a device which moves the coherent tobacco leaves in such a way that separation is effected by air resistance, i. e., the leaves are thrown into an air space in the form of bundles or bunches which are then separated into single 15 leaves by the resistance of the air. The method is carried out by causing the device to impart to the tobacco leaves a uniform or uniformly accelerated motion, the final velocity being chosen so that separation of the leaves takes place by the 20 resistance of the air. For carrying out the process various devices may be employed. For example, the bundles may be rotated by the device about a central point and, simultaneously, be capable of moving away from the pivot while 25 rotating, the speed of the bundles being uniformly accelerated thereby and the resistance of the air insures complete separation of the leaves. The conduit in which the bundles move is bent preferably in wavelike fashion or provided with 30 resistances for effecting separation of the leaves by purely mechanical means also. Or the bundles may be thrown into the air space by a sort of projecting or shooting device, in which case the initial velocity is great enough to insure 35 complete separation by the resistance of the air. Furthermore, several devices provided with catches may be arranged one behind the other to impart increasing speed to the tobacco leaves by providing, for instance, a number of bands one 40 after the other which move at different speeds and throwing the bundles of leaves from the slower band to a speedier one, the division into single leaves taking place with absolute certainty at the point where the resistance of the air effects a separation owing to the high 45 velocity.

The devices carrying out the process in accordance with the present invention may serve as 50 mixing devices also. For this purpose the various kinds of tobacco are guided to the separating means which effect thorough mixing of the different sorts of tobacco when the latter reach the collector. To remove bundle portions which still stick together as well as heavy foreign 55 substances, centrifugal force is utilized by causing the portions that stick together to be thrown beyond the collecting vessel for the separated leaves and catching them separately. This can be effected in a simple manner, since the cohering bundle portions or foreign substances 60

possess a higher specific gravity and, moreover, disclose a much lower air resistance.

If a device is used for separating the tobacco leaves, in which the tobacco portions are forced by a catch or driver to carry out a certain motion, such as, for instance a centrifuge, it becomes possible to obtain the added advantage of cleaning the tobacco during the separating process by constructing the mechanical carrier so that the dust and sand contained in the tobacco may pass 10 through it and into a special chamber. This object can be preferably attained by manufacturing the carrier serving as centrifuge from pervious material in the form of a sieve, fabric or the like, through which the dust particles can pass during 15 the motion of the tobacco. As the dust particles are thrown outwardly by centrifugal force, only the outer surface of the carrier need be made from permeable material.

As the tobacco leaves are moved about in the 20 carrier for a short time only, it is advantageous to dust them still further when they have come out of the carrier. For this purpose another receiving chamber may be provided which surrounds the carrier on all sides and has sievelike 25 walls also. The entire device may be disposed within a single casing which shuts off the device dusttight and takes up, for example, the dust coming out of the carrier or receiving chamber. This casing may be freed from dust by pneumatic 30 or mechanical means.

Owing to the speed of the leaves, the latter are moved through the receiving chamber surrounding the carrier and can be caught in a special container. To insure the removal of cohering 35 bundles or foreign substances, such as stones, coins, nails and the like, from the tobacco in this modification also, an additional receiver is arranged preferably opposite the outlet opening of the receiving chamber for tobacco and at 40 a suitable distance thereof, the separated leaves being taken away between the two receivers while the substances of greater specific gravity are thrown into the second receiver.

The invention, which permits of still other 45 modifications, is illustrated in the accompanying drawing, in which Figures 1 and 2 are, respectively, a side and top view of a device serving exclusively for separating the tobacco leaves; Fig. 3 is a side view, partly in section, of a device for the simultaneous separation and cleaning 50 of tobacco leaves; and Fig. 4, a view of the spiral carrier employed in the modification shown in Fig. 3.

In the modification shown in Figs. 1 and 2, 1 is a 55 hopper for receiving the tobacco bundles of the same or different kinds. The hopper 1 opens into a vertical pipe 2 which in turn opens into a horizontal conduit 3. The entire device can be 60 rotated about the vertical shaft 4. 5 is a driver

which may be constructed to form a belt pulley gear or the like. The direction of rotation is indicated in Fig. 2. The conduit 3 is preferably corrugated and may contain special frictional resistances for holding the leaves. When the device is turned and the tobacco bunches are fed into the hopper 1, the bunches will move at a uniformly accelerated speed and, owing to centrifugal force, will tend to move outwardly through the conduit 3. The resistance of the air and the inner resistances in the conduit 3 separate the bundles completely into single leaves. At the end of the conduit 3 a collector (not shown) is provided for the separated leaves, which, in this case, has a circular shape. The portions of the bundles that are not separated and the heavier foreign substances fly beyond the collector and can be caught separately.

In the modification according to Figs. 3 and 4, 6 indicates the tobacco bundles fed into the hopper 7 through which they pass into the carrier 8 constructed like a centrifuge. The outer walls 9 of the carrier 8 are made from sievelike fabrics to permit the passage of the dust. 10 is the receiving chamber for the tobacco coming out of the carrier 8 and 11 is the discharge conduit for the leaves through which they pass outside from the receiving chamber 5. The entire device is arranged in a casing 12 provided at its lower end with an opening 13 which may be connected to a suction piping to remove the dust particles 14 from the container. 15 is the inlet for the suction air.

After the tobacco has passed through the device it moves on a conveyor 16 passing over the rolls 17, 18. Opposite the opening 11 a funnellike receiver 19 is provided for catching the foreign substances 20 thrown out of the conduit 11 at great speed.

40 The device functions as follows:

The tobacco bunches 1 are conveyed outwardly by the rotation of the centrifuge 8 in the direction of the arrow so that the dust particles 14 are thrown out through the sievelike walls 9 of the carrier 8. The outlet opening of the centrifuge 8 is constructed so as to facilitate the passage of the tobacco into the container 10. The rotation of the centrifuge 8 imparts to the tobacco accelerated motion to such an extent that it is thrown out through the pipe 11 without any trouble and can then be conveyed by means of the band 16. In the same way as to the tobacco, high speed is imparted also to the foreign substances 20 contained in the tobacco, which are thus thrown 55 farther than the tobacco and can be caught by the funnel 19.

Instead of the device shown in the drawing an appliance may be used operating along the lines of a projecting or shooting apparatus so that the bunches are thrown into the air space and the leaves separated from one another. If different sorts of tobacco are fed into the carrier, thorough mixing of the leaves will be effected therein.

I claim:-

65 1. A device for separating coherent tobacco leaves, comprising a mechanical rotating carrier with a piping for the discharge of the leaves, a receiver for the loosened tobacco leaves, a second receiver for catching coherent leaf portions and foreign substances contained in the tobacco, the coherent leaf portions being projected by centrifugal force beyond the receiver for the tobacco leaves and caught by the second receiver, and a conveyor for the separated leaves.

70 2. A device for separating coherent tobacco

leaves, comprising a mechanical rotating tubelike carrier made of permeable material to permit the passage therethrough of dust and sand contained in the tobacco leaves, a receiving chamber for the tobacco, and a dust chamber for catching 5 the dust and sand coming out of said permeable carrier and receiving chamber.

3. A device for separating coherent tobacco leaves, comprising a mechanical rotating tubelike carrier made of permeable material to permit the 10 passage therethrough of dust and sand, a receiving chamber for tobacco leaves surrounding said carrier made of permeable material to permit dust and sand contained in the tobacco leaves to pass through it, a dust chamber adapted to receive 15 the dust and sand coming out of the receiving chamber, and conveying means disposed behind the outlet to said receiving chamber and adapted to move the tobacco leaves.

4. A device for separating coherent tobacco 20 leaves, comprising a mechanical rotating tubelike carrier made of permeable material, a tobacco receiving chamber surrounding said carrier and made of permeable material to permit dust and sand contained in the tobacco to pass through 25 it, a dust chamber surrounding said tobacco receiving chamber dust tight on all sides and adapted to receive the dust coming out of said receiving chamber and the mechanical tubelike carrier, conveying means disposed behind the receiving chamber and adapted to move the tobacco leaves, and means for pneumatically removing the dust and sand from the dust chamber.

5. A device for separating coherent tobacco leaves, comprising a mechanical rotating carrier, 35 a tobacco receiving chamber surrounding said carrier and made of permeable material to permit the passage of dust contained in the tobacco leaves, a dust chamber adapted to receive the dust and sand coming out of said receiving chamber, conveying means connected to said receiving chamber and adapted to move the tobacco leaves, and a second receiver disposed opposite the receiving chamber at a distance therefrom and adapted to catch substances contained in the 45 tobacco leaves discharged between the tobacco receiving chamber and said receiver.

6. A device for separating packs of bundled tobacco leaves by exposing them to the action of a rotating carrier of sufficient length, comprising a rotating shaft, a tube connected at one end to said shaft and having an opening at this end for the entrance of the bundled tobacco leaves, and means arranged on the rotating other end of said tube for discharging the separated tobacco leaves.

7. A device for separating packs of bundled tobacco leaves by exposing them to the action of a rotating carrier of sufficient length, comprising a vertical rotating shaft, a tube connected at one end to said shaft and having an opening at this end for the entrance of the bundled tobacco leaves, and means arranged on the rotating other end of said tube for discharging the separated tobacco leaves.

8. A device for separating packs of bundled tobacco leaves by exposing them to the action of a rotating carrier of sufficient length, comprising a horizontal rotating shaft, a tube connected at one end to said shaft and having an opening at 70 this end for the entrance of the bundled tobacco leaves, and means arranged on the rotating other end of said tube for discharging the separated tobacco leaves.
